(57) CLAIM

The ornamental design for a wearable purse, as shown and described.

DESCRIPTION

FIG. 1 is a perspective view of a wearable purse;
FIG. 2 is a front elevation view of thereof;
FIG. 3 is a right side view thereof (left being mirror image);
FIG. 4 is a top view thereof;
FIG. 5 is a rear elevation view thereof;
FIG. 6 is a right side view thereof (left being mirror image);
FIG. 7 is a bottom plan view thereof;
FIG. 8 is a perspective view of a second embodiment of a wearable purse;
FIG. 9 is a front elevation view of the embodiment shown
in FIG. 8;
FIG. 10 is a right side view of the embodiment shown in
FIG. 8 (left being mirror image);
FIG. 11 is a top view of the embodiment shown in FIG. 8;
FIG. 12 is a rear elevation view of the embodiment shown
in FIG. 8;
FIG. 13 is a right side view of the embodiment shown in
FIG. 8 (left being mirror image); and,
FIG. 14 is a bottom plan view of the embodiment shown in FIG. 8.

The broken line showing of environment in the drawings is for illustrative purposes only and forms no part of the claimed design.
